UNITED STATES PATENT OFFICE.

GEORGE P. JACKSON, OF FLUSHING, NEW YORK, ASSIGNOR TO COMBUSTION ENGINEERING CORPORATION, OF NEW YORK, N. Y., A CORPORATION OF NEW YORK.

PULVERIZED-FUEL-BURNING APPARATUS.

Application filed February 29, 1924. Serial No. 695,969.

This invention relates to furnaces and is especially useful in connection with furnaces for burning fuel in suspension, such as pulverized coal, on the stationary boilers.

5 One of the primary objects of my invention is to provide an improved manner of regulably admitting air for combustion, particularly in furnaces fired from more than one side, as for example, in furnaces fired from 10 opposite sides.

Another of the objects of the invention has to do with an improved method of supporting the various portions of the refractory structure constituting the combustion chamber, 15 whereby simplicity is obtained and expansion and contraction of the various parts provided for.

20 My invention also contemplates the novel construction, arrangement and combination of parts hereinafter more particularly to be pointed out.

How the foregoing, together with such other objects and advantages as may herein-after appear, are incident to my invention, 25 is illustrated in the accompanying drawings wherein:

The figure is a vertical section through a furnace and boiler illustrating my improvements.

30 Referring now to the drawings the reference character A denotes the combustion chamber which is constructed in the following manner.

A suitable supporting base or structure 7, preferably of concrete material is provided 35 and upon this base the upright wall B forming the sides of the combustion chamber, is erected. For reasons which will hereinafter appear, the base 7 is in the nature of a double hopper in so far as its physical form is con-

cerned. The bottom or bottom wall 8 of the combustion chamber is a refractory lining built up upon and supported by the base in the manner shown. It will be seen from inspec-

45 tion of the figure that the upright or side wall of the combustion chamber and the bottom thereof are carried on the base independently of one another whereby, in the first place the load of the side wall is not imposed upon the bottom wall of the combustion chamber,

50 and, in the next place the bottom wall can expand or contract freely with respect to the side wall. The top, roof or arch walls 9 of the combustion chamber, are supported from the metallic beam structure 10 independently

of the side wall of the combustion chamber, 55 with freedom for expansion and contraction of the arches and the side wall, independently of one another.

The combustion chamber, as a whole, is rectangular in horizontal cross section, with 60 a horizontal dimension (at least in the plane of the firing) greater than vertical dimension, i. e. the combustion chamber is longer than high and is of a width suitable to accommodate the number of burners required 65 to deliver the quantities of fuel it is desired to burn.

The upright wall is composed of an outer shell 11 and an inner shell 12, spaced apart so as to produce a hollow wall. At various 70 points in the elevation of the side wall there are rows of tying-in bricks 13, dividing the space between the shells into horizontal compartments extending around the combustion chamber. These tying-in bricks secure the 75 two shells together but with freedom for the two shells to expand and contract with reference to one another. The specific means for attaching the tying-in bricks to the outer shell is not shown as it forms no part of this 80 invention, specifically considered, and it will suffice to point out that it is such as to permit vertical movement of the tying-in bricks with respect to the outer shell.

The pulverized coal is admitted simulta- 85 neously on opposite sides of the combustion chamber by rows of burners 14, arranged to admit the fuel, preferably with a portion of the air required for combustion, in a down- 90 ward direction adjacent the respective oppos- 95 ing sides of the combustion chamber. The number of burners varies with the particular installation.

The descending fuel and flame streams are ignited shortly after admission into the cham- 95 ber, and continue to descend until their down- 100 ward momentum is overcome by the draft, whereupon the fuel and flame streams are turned in toward the center and thence up- 105 wardly to the outlet 15 of the combustion chamber each stream taking a substantially U-shaped course, with the ascending legs uniting in one general leg. The bend in the fuel and flame streams is well above the bottom of the combustion chamber.

Since only a portion of the air required for combustion is supplied with the coal, the balance required is admitted through the hol-

low wall of the combustion chamber as will now be described. The inner shell 12 at the opposing sides, adjacent to which the fuel streams are admitted, is provided with a horizontal row of openings 16 establishing communication between each compartment in the hollow wall and the interior of the combustion chamber. At an intermediate point, i. e. preferably in the middle of the side walls 10 connecting the portions having the opening 16, are damper controlled air inlets 17, which admit air to each compartment, the air flowing from the point of inlet around the combustion chamber through the respective compartments, entering the combustion chamber through the inlets 16. The damper controlled inlets 17 permit of regulation of the quantity of the air admitted to all of the compartments and to each of the 20 compartments so that a very flexible system of air control is provided whereby the precise quantities of air needed to burn the fuel in the most effective manner are delivered in accordance with the needs of combustion as combustion proceeds. The air in passing in opposite directions through the wall to the point of inlet into the combustion chamber is heated by the absorption of heat from the walls. This has a beneficial 25 effect on combustion and furnace temperatures and also serves to protect the refractories from the temperature prevailing within the combustion chamber. Air, if desired, may also be admitted through the damper 30 controlled inlets 18, it being possible to admit all of the air for combustion either through the inlets 17 or the inlets 18, or any proportion of the air required may be admitted through both.

40 In the lower part of the combustion chamber I provide two water screens C and D each consisting of a plurality of tubes 19 which pass out through the bottom of the combustion chamber at about the middle portion 45 thereof where they connect with a header 20. Each set of tubes 19 has such a header and such tubes are inclined and passed out through the upright wall for connection with a header 21 which header is connected into the circulation of the boiler by a plurality of risers 22, as shown. The headers 20 are connected by relatively large downcomer pipes 23 to the water spaces or drums of the boiler. The function of the water screens 50 55 is to create a cooled zone in the bottom of the combustion chamber through which precipitating refuse particles fall and by which they

are cooled below the fusion point. This refuse collects in the hoppers, of which there is one beneath each fuel and flame stream 60 and from which the refuse may be removed from time to time substantially in the form of a powder.

To assist in creating the cooling zone and to protect the bottom refractories and to absorb heat from the deposit I prefer to make the bottom hollow as shown, the preferred arrangement being the provision of a plurality of ducts or compartments 24 through 65 which air may be drawn or blown through a manifold 25 having a fan, the heated air being either introduced into the compartments of the upright wall or to the feeder mechanisms supplying the burners.

The boiler setting 26 is carried on the beams 75 10 as shown in a manner to be independent of the arches and the side wall.

The curvature in the pipes 23 takes care of expansion and contraction as between the two points, i. e. the headers 20 which are supported in the manner shown and the drums. The tubes 19 expand from or contract toward the middle of the combustion chamber because of the loose filling material 28 inserted in the openings in the upright wall through which the tubes pass. The risers 22 are hung from the beams 27 and contraction and expansion takes place below the point of support because of the loose sealing material 28, and takes place above such 90 point by virtue of the bends in the risers.

I claim:

1. In combination, a combustion chamber, means for introducing pulverized coal downwardly simultaneously from opposite sides, 95 and said combustion chamber having a bottom in the form of a double hopper the outer wall portion of which is hollow, together with means for admitting a cooling medium into said hollow portion.

2. In combination, a combustion chamber having a central outlet in the upper part thereof, means for admitting fuel to the chamber downwardly from opposite sides thereof so that each fuel and flame stream will describe a U-shaped course from the point of admission to the outlet, means for admitting air into an upright wall of the chamber at a point intermediate the points of fuel admission and conducting the same 105 through the wall and into the chamber.

In testimony whereof, I have hereunto signed my name.

GEORGE P. JACKSON.
